UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed September 17, 1923, Serial No. 663,058. Renewed September 15, 1928.

The present invention relates to multi-office telephone systems in general, but is concerned more particularly with such multi-office systems as employ directors to route the calls; and the broad general object is the production of new and improved circuit arrangements for the directors and their associated apparatus whereby their various operations are performed in a simpler and more reliable manner.

Specifically one of the objects of the present invention is the production of a new and improved vibrating interrupter individual to a director for the purpose of controlling the sending equipment.

Another object is the production of new and improved circuit arrangements whereby the stepping magnet of the sending switch, in addition to operating the sending switch in its step by step movement to count off the interruptions produced in the outgoing control circuit, produces the necessary interruptions in the outgoing control circuit to control the automatic switches.

Another object is the production of new and improved circuit arrangements whereby one single skip conductor may be provided to enable the sending sequence switch to skip over any one of the four positions allotted to the sending out of the office code. Formerly one skip conductor was required for each code digit to be skipped.

Another object is the production of a simplified arrangement for preventing the sending equipment from advancing ahead of the registering mechanism when the calling subscriber is slow in dialling the remaining part of the number.

Another object is the production of suitable circuit arrangements whereby the first selector switch is unresponsive to the operations of a subscriber's calling device in case he waits so long before dialling the first digit that the call has been switched through automatically to a first selector in order to free the director for another call. This is to prevent a call from "going wild" with the likelihood of annoyance to another subscriber, which might happen in case a calling subscriber were permitted to operate the switches, it being understood, of course, that the first part of the number is translated by the director.

A further object of the invention is the pro-

duction of suitable circuit arrangements whereby the resistance of the loop through which automatic switches are controlled by the sending equipment of a director is decreased, when a very long inter-office trunk is taken for use, in order to secure the proper operation of the remaining switches in the train.

A still further object is the production of new and improved circuit arrangements whereby the selecting switch which is individual to a first selector trunk and which selects a director when a call is made, is caused to step ahead one step when the director in use "switches through" and is freed. This is done to insure an equal distribution of the traffic amongst the various directors and in order to prevent a calling subscriber from getting the same director repeatedly, and thereby be prevented from getting service, in case the director in question is out of order.

A still further feature of improvement contained in the present case is the arrangement whereby, on calls to the toll recording operator, the operator is reached over any one of a plurality of groups of trunks, depending upon the kind of service or the extent of the service to which the instant calling subscriber is entitled. Specifically the director is arranged to send out three different numbers, one for each of the three classes into which it is assumed that the calling subscribers are divided. The same arrangement is provided in connection with calls that are to be trunked to the so called "express operator", that is, the operator which gives rapid service between two cities or suburbs located close together, or between a city and any one of the suburbs.

Still another feature of the invention relates to the provision of suitable circuit arrangements for cutting in a separate low resistance battery supply for the calling line when an express call is answered. This avoids the necessity of providing a separate group of trunks for giving express service, which can then be given over the same trunks that are used for giving local service.

There are several other novel features disclosed, having to do mainly with the various circuit details employed in carrying out the principles of the invention set forth above. These features, together with the foregoing, will be explained fully hereinafter in con-

nection with the accompanying drawings comprising Figs. 1-7, inclusive.

Referring now to the accompanying drawings which show by means of the usual circuit diagrams a sufficient amount of equipment in a telephone system embodying the principles of the invention to enable the invention to be understood and its utility appreciated, Figs. 1-3, inclusive, show the equipment which may be used in setting up a connection from a calling automatic substation A by way of an express operator's position to a called manual substation B, while Figs. 4-7, inclusive, show one of the directors.

Referring now particularly to Figs. 1-3, inclusive, Fig. 1 shows a substation A, of which the line terminates at the exchange in the line switch C which in turn has access to the selector D, Fig. 2, by way of the repeater R. The repeater R has an associated individual secondary switch SS which has access to a number of directors of which the one shown in Figs. 4-7, inclusive, is one.

Fig. 2 shows the selector D, which is individual to the repeater R and which has access to a number of second selectors of which one is the selector E—indicated by the dotted rectangle bearing that reference character. The selector E has access to a number of selectors of which one is the selector F, which selector in turn has access to a number of trunks, of which the one comprising conductors 151 and 152 is one. This trunk is a two conductor trunk and it extends to the office in which the express service operator is located, and terminates there in the plug ending cord circuit CC.

In addition to the trunk comprising conductors 151 and 152, two other trunks are shown accessible to the selector F. It is assumed that the trunk comprising conductors 151 and 152 is one of the group of trunks over which unlimited express service calls are handled. It is assumed that the trunk comprising conductors 161 and 162 belongs to the group of trunks over which calls originated by limited service subscribers are handled. It is assumed further that the trunk comprising conductors 171 and 172 is one of the group of trunks over which calls originated by subscribers not entitled to any express service are handled. These three group of trunks may all extend to the same operator's position or they may be extended to three different operator's positions, depending of course upon the local requirements.

Fig. 3 shows, in addition to the cord circuit CC, the cord circuit CC' to which connection can be extended from the cord circuit CC by way of jack J and the inter-office trunk comprising conductors 221 and 222. The office in which the cord circuit CC' is located lies beyond the limit of local service and calls to it are handled by means of the express service and charges are made accordingly.

Fig. 3 shows also the substation B and the associated line which terminates at the exchange in the jack J', and shows, in addition, the inter-office order wire OW, together with the operators' head sets at either end, and the push button P.

Referring now particularly to Figs. 4-7, inclusive, the portion of the director shown in Fig. 4 comprises the four control relays 306-309, inclusive, and the sequence switch S, together with the four digit register DR-1-DR-4, inclusive; the portion of director shown in Fig. 5 comprises the sending switch SEN and the relays 410 and 411, together with the vibrating interrupter 412; the portion of director shown in Fig. 6 comprises the office register OR and the intermediate distributing frame IDF; and the portion of the director shown in Fig. 7 comprises the relays 611, 619, 620, 601, and 602, and the sequence switch S'.

The line switch C, Fig. 1, is mechanically of the well known rotary type in which the wipers have no normal position and move in a forward direction only.

The selector D, Fig. 2, as well as the selectors indicated by the dotted rectangles E and F, is mechanically of the well known vertical and rotary type in which the bank contacts are arranged in horizontal rows or levels. The office register OR of the director, Fig. 6, is mechanically of the same type of switch as the selector D.

The sequence switch S, Fig. 4, is mechanically a simple type of switch, having the wipers 333 and 334, which are advanced over the associated bank contacts by the stepping magnet 331, and which are restored to normal position upon the energization of release magnet 332, whose circuit is controlled by off normal contacts 336. The mechanical connection between the armature (not shown) of stepping magnet 331 and wipers 333 and 334 is such that the said wipers are advanced upon the back stroke rather than upon the front stroke of the armature. Accordingly it is necessary to provide means for energizing the stepping magnet 331 upon the release of the wipers in order to pull the associated pawl free from the ratchet wheel. This is accomplished by the armature 335 on the release magnet 332 which completes a circuit for the stepping magnet.

The digit registers DR-1 to DR-4, inclusive, are each mechanically similar to the sequence switch S except that their wipers are advanced upon the energization of their associated stepping magnets rather than upon the deenergization.

The sending switch SEN, Fig. 5, is mechanically of the well known rotary type of switch, having wipers which move in a forward direction only. The wipers of the switch are advanced upon the deenergization rather than upon the energization of the step-

130

ping magnet 403, which is indicated schematically in the drawing. The sequence switch S', Fig. 7, is mechanically similar to the sending switch SEN, except as regards the 5 number of wipers employed.

The system and the apparatus shown having been directed more or less in general, a detailed description of the operation of the equipment shown in the drawings will now 10 be given. For this purpose it will be assumed that the subscriber at substation A desires to call a subscriber whose line terminates at the office which is listed in the directory as office number 70 or is listed by name and that the 15 first two letters of its name corresponds to the numerals 7 and 0, respectively, it being understood of course that the letters of the alphabet are often placed on the calling device in addition to the numerals 1 to 0. It will be 20 assumed further that the complete number of the desired station is 70-0987, the numerals 7 and 0 representing the office and the remaining part of the numbers signifying the particular subscriber desired in that office.

25 When the receiver is removed at substation A, line relay 15 of the line switch C operates over line conductors 11 and 12 and places ground on private normal conductor 13 at armature 22, thereby making the calling line 30 busy to the connector switches having access to it and also closing a circuit through switching relay 14 and stepping magnet 20 in series. As a further result of the energization of the 35 line relay 15 it connects test wiper 24 to the junction of switching relay 14 and line relay 20 at armature 21.

The further operation depends upon 40 whether the trunk upon which the wipers of the line switch are standing is busy or idle. Assuming the trunk to be busy, test contact 28 is grounded over conductor 32 and the ground potential is extended through test wiper 28, armature 17, and its resting contact, and the working contact of armature 21 45 and said armature to the junction of switching relay 14 and stepping magnet 20. Switching relay 14 is short circuited by this ground potential and does not energize and stepping magnet 20 energizes and interrupts 50 its own circuit, thereby advancing the wipers 23-26, inclusive, step by step until test wiper 24 engages on ungrounded test contact.

In the present case, however, it will be assumed that the trunk upon which the wipers 55 of the line switch are standing is idle. That being the case switching relay 14 is not short circuited and accordingly energizes in series with stepping magnet 20 immediately following the above mentioned energization of line relay 15. Stepping magnet 20, however, is not energized at this time on account of the high resistance of switching relay 14. Upon energizing, switching relay 14 disconnects test wiper 24 from the junction of its own 60 winding and that of the stepping magnet 20

and connects it to the grounded private normal conductor 13, thereby preparing a holding circuit for itself and simultaneously making the seized trunk busy. As a further result of the energization of switching relay 14 70 it disconnects line conductors 11 and 12 from the windings of the line relay 15 and ground, at armatures 16 and 19, and extends them by way of wipers 23 and 26, bank contacts 27 and 30, conductors 31 and 34, and the normally closed contacts controlled by armatures 51 and 52 to the upper and lower windings of the double wound line relay 44 of the repeater R. Line relay 44, upon energizing, 75 closes a circuit for release relay 46 at armature 57 which extends through the resistance 49 to battery. Release relay 46, upon energizing, places ground on release trunk conductor 32 at armature 60, thereby completing the holding circuit for switching relay 14 of 80 the line switch C before the slow acting line relay 15 has had time to deenergize. As a further result of the energization of release relay 46 it closes at armature 62 a circuit for the polarizing winding of the electropolarized relay 45. Relay 45, however, does not 85 energize at this time on account of the fact that its polarizing winding is composed of a comparatively small number of turns of wire having a relatively high resistance. 90

As a still further result of the energization of release relay 46 of the repeater R, it closes at armature 61 a circuit through armature 69 and its resting contact for switching relay 81 and stepping magnet 82 of the secondary switch SS in series, and at armature 64 connects test wiper 91 to the junction of switching relay 81 and the stepping magnet 82, through the resting contact of armature 67 and said armature, and the resting contact of armature 85 and said armature. The closure of these two circuits results in the secondary switch SS selecting an idle trunk in the same manner as above described for the line switch C, and, assuming that the trunk upon which the wipers of the secondary switch are standing is idle, the wipers are not rotated and switching relay 81 energizes immediately. Switching relay 81, upon energizing, disconnects test wiper 91 from the junction of its own 105 windings and those of stepping magnet 82 and connects it to ground at armature 85, thereby making the seized director busy immediately by grounding test conductor 302 through bank contact 96. Switching relay 81 also connects up wipers 89, 90, 92, and 93 at armatures 83, 84, 86, and 88, respectively, and at armature 87 prepares a circuit for stepping magnet 82 which will be closed subsequently. 110

With wipers 89 and 93 of the secondary switch SS connected up at armatures 83 and 88, respectively, a bridge is placed across conductors 71 and 73 extending from the repeater R to the selector D, Fig. 2. This bridge in 115

cludes wipers 89 and 93, bank contacts 94 and 98, conductors 304 and 305, contacts 404 of the stepping magnet 403, of the sending switch SEN, Fig. 5, and resistance 637, Fig. 7. Responsive to the closure of this bridge line relay 115 of the selector D energizes and closes a circuit for release relay 116 at armature 126. Release relay 116 thereupon energizes and places a multiple ground on release trunk conductor 72 at armature 127 and at armature 128 opens a point in the circuit of release magnet 120 and prepares a circuit for vertical magnet 122.

In the director, release relay 308 which is connected directly to the conductor 302 energizes, in response to conductor 302 being grounded through test wiper 91 of the secondary switch SS as pointed out above, and at armatures 317 and 316 removes ground from conductors 353 and 352, thereby opening at these points the restoring circuits of various mechanical switches of the director. Relay 308 also opens the normal restoring circuit of the sending switch SEN, Fig. 5, at armature 314, and at armature 315 connects the common timing conductor 321 to the upper winding of the marginal two step relay 306 through armature 311 and its resting contact.

As a further result of the ground potential being placed on the release trunk conductor 302, a circuit is closed through the resting contact of armature 421 of start relay 411, Fig. 5, for the magnet 412 of the individual vibrating interrupter V. Magnet 412 thereupon becomes energized and attracts the associated armature, causing the pendulum 413 to be pulled to the left and remain in this position preparatory to the first sending operation.

The director is now in readiness to receive the desired number, but, before the description of how the number is received is given, the operations involved in switching the call through to the first selector D, Fig. 2, in case of too long a wait before the first digit is dialled will be described. For this purpose, it will be assumed that the calling subscriber, having removed his receiver with the above described results, fails to dial his number right away, and instead turns to other business, leaving the receiver off the hook. In this case, if it were not for the special provisions that are made, the director would be tied up indefinitely. The way in which this is prevented will now be described. As soon as ground is placed upon the common conductor 321, Fig. 4, by the springs controlled by the cam wheel 310, after the energization of release relay 308, a circuit is closed through armature 311 and its resting contact for the upper winding of the marginally adjusted two step relay 306. Relay 306 energizes at this time only far enough to bring armature 312 into engagement with its associated contact but it does not operate

armature 311. Armature 312 by coming into engagement with its associated contact locks relay 306 to the grounded release trunk conductor 302 through the lower winding of the said relay. This locking circuit is not effective to energize the lower winding of the relay at this time owing to the fact that the said winding is short circuited by the ground potential which is applied through armature 311 and its resting contact.

When ground is subsequently removed from the common conductor 321 the initial circuit of the upper winding of relay 306 is broken and the circuit for the two windings of the relay in series becomes effective, whereupon the relay operates fully and armature 311 is brought into engagement with its working contact, thereby preparing a circuit for switching relay 309, which includes conductor 351, off normal contacts 500 of the office register OR, switching conductor 354, and the normally closed contacts controlled by armature 319.

After an interval (for example, fifteen seconds) which is sufficiently long to permit the calling subscriber to dial the first digit in the number and thereby cause the office register OR, Fig. 6, to be moved off normal, even granting a reasonable amount of delay on the part of the calling subscriber, the cam 310, Fig. 4, again operates its contact springs, thereby placing ground on conductor 321 which results in the above traced circuit through armature 311 and its working contact for switching relay 309 being closed. Switching relay 309 thereupon energizes and locks itself to conductor 302 at armature 319, at the same time opening its initial circuit. As a further result of the energization of switching relay 309 it opens the incoming impulsive circuit, which includes series relay 307, at armature 318, and closes a circuit for switching relay 48 of the repeater R as follows: from ground by way of resistance 638 associated with relay 601, Fig. 7, conductor 360, working contact of armature 318 and said armature, conductor 303, bank contact 97, wiper 92 of the secondary switch SS, armature 86 and its working contact, armature 58 of line relay 44 and its working contact, marginal relay 47, and the upper winding of switching relay 48 to battery. Switching relay 48 energizes over this circuit, but relay 47, being marginally adjusted, does not energize on account of the inclusion of resistance 638, Fig. 7, in the circuit. Relay 48, upon energizing, places at armatures 71 and 73, a second bridge across conductors 71 and 73 in multiple with the one already closed in the director. This second bridge includes the lower winding of the electro-polarized relay 45 and the right hand winding of the impedance coil 50. Electropolarized relay 45 does not energize responsive to the closure of this bridge owing to the fact that the current

70

110

115

120

125

130

flow through its lower winding is in such a direction as to set up lines of force in opposition to those produced by the current flow in the upper winding.

5 As a further result of the energization of switching relay 48, it opens the circuit of the slow acting switching relay 81 and closes a locking circuit for itself at armature 69. This locking circuit includes the working contact 10 of armature 61 of release relay 66 and its resting contact and lower winding of relay 48. The opening of the circuit of switching relay 81 of the secondary switch SS results in the de-energization of said relay 81 after an interval. 15 During this interval a circuit is closed in multiple with the lower winding of relay 48 and through armature 87 of the said relay 81 and its working contact for stepping magnet 82. Stepping magnet 82 accordingly energizes, 20 but, owing to the fact that the associated wipers are advanced only on the back stroke of said magnet, the wipers are not advanced at this time and the pawl of the armature of the magnet 82 (not shown) is merely moved into engagement with another 25 notch on the ratchet wheel which drives the associated wipers.

After a momentary interval, switching relay 81 lets go, thereby freeing the director, and 30 at the same time opens the circuit of stepping magnet 82, whereupon the wipers 89-93, inclusive, are advanced into engagement with the next set of bank contacts. This is the hereinbefore mentioned expedient employed 35 to insure that two successive calls over the same trunk do not take the same director for use unless all the others happen to be busy.

As a result of the deenergization of the 40 switching relay 81, the previously traced bridge across conductors 71 and 73 in the director is opened at armatures 83 and 88, leaving the line relay of the selector D energized solely through the bridge which is now closed across conductors 71 and 73, in the repeater R, 45 at armatures 68 and 71 of the switching relay 48.

In the repeater R, switching relay 48 also 50 separates conductors 101 and 102 at armature 70, thereby opening the circuit of the vertical magnet 122 of the selector D so as to prevent the switch from being operated in case the calling subscriber later returns to the phone and starts to manipulate his calling device before first replacing his receiver long enough 55 to break down the connection between his line and the selector D.

As above pointed out, the director, which 60 is a comparatively expensive organization of equipment, is freed and the call is switched through to the selector D where it will soon be detected as a "permanent" by an attendant who is notified of the condition by means of the usual supervisory equipment (not shown) 65 associated with the selector D for that purpose. The expression "permanent", it will be

understood, is the term ordinarily applied to the above explained condition wherein no dialling occurs after the first selector is seized, as distinct from a genuine call in which the first selector is operated shortly after its 70 seizure.

In the director, relays 306, 308, and 309, Fig. 4, together with magnet 412 of the vibrator V, Fig. 5, deenergize. The deenergization of the relays mentioned, restores the circuit conditions in the director to normal, and the deenergization of magnet 412 of the vibrator V results in the release of the associated pendulum 413 which starts to vibrate, and on each outward swing, closes the contacts 414. 80 This does not cause any harm to result, however, owing to the fact that start conductor 359 is not grounded at this time and the vibrator V presently comes to rest, after about thirty or forty vibrations. 85

It will now be assumed that the subscriber at substation A, in making this call, does not wait unduly long before dialling, as was assumed in the case just described, but that, after having removed his receiver with the 90 result described hereinbefore, he listens for the dial tone and then proceeds to dial as soon as he hears it. The dial tone, it may be mentioned, is placed on the impulse conductor by the dial tone transformer 505, Fig. 6. The 95 tone induced in the right hand winding of the transformer 505 passes through the vertical magnet 504 and thence flows by way of conductor 337, the first contact in the upper bank of sequence switch S, Fig. 4, wiper 333, series relay 307, resting contact of armature 318 and said armature, conductor 303, bank contact 97, wiper 92, armature 86 and its working contact, armature 57 and its working contact, condenser 74, resting contact of armature 71 and 100 said armature, and thence by way of the lower heavy talking conductor to the substation A. The calling subscriber, upon hearing the distinctive tone produced in his receiver by this current, knows that he may now call the desired number. 110

When the calling subscriber manipulates his calling device in accordance with the first office digit 7, a corresponding number of interruptions are produced in the circuit of line 115 relay 44 of the repeater R, resulting in seven momentary deenergizations of the said line relay 44. Upon each of these deenergizations line relay 44 short circuits release relay 46 at armature 57. However, as is well known, 120 a relay short circuited in this manner has the characteristics of a slow acting relay and is even more constant in its tendency to maintain its armature attracted for an interval than if it were provided with a copper collar 125 and its circuit merely opened. Accordingly, release relay 46 is not deenergized but maintains its armature attracted through the series of deenergizations of line relay 44. As a further result of each deenergization of line 130

relay 44, it disconnects the combined impulse and switching conductor from switching relays 47 and 48 and connects it to ground at armature 58, thereby completing a circuit for vertical magnet 504 of office register OR, Fig. 6, which extends from ground through the resting contact of armature 58 and said armature, working contact of armature 86 and said armature, wiper 92, bank contact 97, conductor 303, armature 318 and its resting contact, series relay 307, wiper 333 of the sequence switch S, the first associated bank contact, conductor 337, vertical magnet 504, and the right hand winding of the dial tone transformer 505 to battery. By the operation of vertical magnet 504, which is energized each time the above circuit is closed, the wipers 511-514, inclusive, of the office register OR are raised step by step until they stand opposite the seventh level of bank contacts. Relay 307 is energized in series with vertical magnet 504 upon the first energization of the latter and, being slow acting, maintains its armature attracted throughout the entire series of impulses. Upon energizing, relay 307 closes at armature 313 a circuit for stepping magnet 331 of the sequence switch S. Stepping magnet 331, upon energizing, does not advance the wipers 333 and 334 but merely makes ready to advance them when it is subsequently deenergized.

Responsive to the wipers of the office register OR being moved from their normal position, the off normal contacts 500 and 501 are operated, and the off normal contacts 500 disconnect conductor 351 from conductor 354, thereby removing switching relay 309 from under the control of timing relay 306.

At the end of the series of impulses delivered to the vertical magnet 504 of office register OR, series relay 307, Fig. 4, deenergizes and opens the circuit of stepping magnet 331 of the sequence switch S, whereupon the said magnet deenergizes with the result that the wipers 333 and 334 are advanced into engagement with the next set of associated bank contacts.

The calling subscriber may now operate his calling device in accordance with the second office digit 0, resulting in a series of ten impulses of the current being sent to the rotary magnet 503 of the office register OR over the circuit previously traced for the vertical magnet 504 as far as wiper 333 of the sequence switch S, Fig. 4, and from thence by way of the second associated bank contact and conductor 338. As a result, rotary magnet 503 energizes ten times and advances the wipers 511-514, inclusive, into engagement with the tenth set of bank contacts in the seventh level which are the four contacts indicated as (70) in the drawing.

Series relay 307, Fig. 4, at this time energizes as before described, resulting in the wipers of the sequence switch S being ad-

vanced into engagement with the third set of associated bank contacts. Wiper 334, upon coming into engagement with the third set of associated bank contacts, places ground upon start conductor 357, thereby initiating 70 the operation of the sending equipment with the results which will be explained hereinafter.

The calling subscriber may now manipulate his calling device in accordance with the first subscriber digit 0, resulting in ten impulses of current being delivered over the above traced circuit to wiper 333, and thence by way of the third associated bank contact to the first digit register DR-1. The wiper 80 343 of the digit register DR-1, accordingly advances into engagement with the tenth associated bank contact.

At the termination of the operation of the digit register DR-1, the wipers of the sequence switch S are advanced, and in the same manner as described for digit register DR-1, the digit registers DR-2, DR-3 and DR-4 are set, the wiper of the digit register DR-2 being set upon the ninth associated bank contact, the wiper of the digit register DR-3 upon the eighth associated bank contact, and the wiper of the digit register DR-4 upon the seventh associated bank contact. 95

At the termination of the setting of digit register DR-4, wipers 333 and 334 of the sequence switch S are advanced into engagement with the seventh set of associated bank contacts in which position they remain until 100 the director is released.

The operation of the sending equipment, which is started, as above pointed out, at the termination of the setting of the office register OR, will now be taken up. When ground 105 is placed upon start conductor 357 by wiper 334 of the sequence switch S, a circuit is closed through the first contact in the bank of wiper 655 of the sequence switch S', Fig. 7, wiper 655, conductor 359, resting contact 110 of armature 419 and said armature, and start relay 411 to battery. Start relay 411, upon energizing, prepares a locking circuit for stop relay 410 at armature 420, and at armature 422 places ground, through armature 418 and its resting contact, on conductor 407, thereby closing a circuit for stepping magnet 651 of the sequence switch S', Fig. 7. Stepping magnet 651 now energizes, whereupon the associated pawl is moved into engagement 120 with the next notch on the wiper driving ratchet wheel, but the associated wipers 653-656, inclusive, are not operated. As a further result of the energization of start relay 411, it opens the circuit of magnet 412 125 of the vibrator V, whereupon the said magnet deenergizes and frees the pendulum 413 which starts to vibrate at the proper rate for sending out the switch control impulses.

Each time the contacts 414 are closed when 130

the pendulum 413 swings away from the magnet 412, a circuit is closed from the grounded start conductor 359 for stepping magnet 403 of the sending switch SEN. Upon each energization of stepping magnet 403, its armature is attracted and the associated pawl is moved into engagement with the next notch in the associated wiper driving ratchet wheel, and, upon each deenergization of stepping magnet 403, the associated armature is retracted, resulting in the wipers 401 and 402 being advanced one step.

As a further result of each energization of stepping magnet 403, it opens the bridge across conductors 304 and 305 at contacts 404, and consequently opens the circuit of line relay 115 of the selector D, with the result that the selector D is operated in a manner to be explained subsequently.

Since the first digit to be sent out is the digit "3", the vibrator V continues to vibrate and the wipers 401 and 402 of the sender SEN continue to be advanced step by step by the operation of stepping magnet 403 under the control of vibrator V until the three impulses have been sent out, at which time wiper 402 arrives upon the fourth associated bank contact which is the contact in which the third impulse stop conductor terminates. At this time a circuit is closed for stop relay 410 of the sender SEN as follows: from ground by way of the stop conductor control wiper 654 of the sequence switch S', the first associated bank contact, the first office digit stop conductor 521, wiper 511 of the office register OR, the bank contact upon which the said wiper 511 is standing, conductor 541, the associated jumper on the intermediate distributing frame IDF, the third impulse stop conductor 583, the fourth contact in the bank of wiper 402 of the sender SEN, Fig. 5, wiper 402, and stop relay 410 to battery. Stop relay 410 now energizes to terminate the first office code digit 3, and disconnects start relay 411 from start conductor 359 at armature 419, leaving the circuit of relay 411 closed through wiper 401 and the grounded bank contact upon which it is standing.

Stop relay 410 also opens the circuit of stepping magnet 651 of the sequence switch S' at armature 418, whereupon stepping magnet 651 deenergizes and the wipers of the sequence switch are advanced one step.

As a further result of the energization of stop relay 410 it closes at armature 418 a holding circuit for magnet 412 of the vibrator V, whereupon magnet 412 becomes energized again and attracts and holds the pendulum 312 preparatory to the next series of impulses to be produced at contacts 414. As a further result of the energization of stop relay 410, it connects wiper 401, which is now standing on a grounded bank contact, with stepping magnet 403 at armature 415

through the interrupter contacts 405, and at armature 427 places a shunt around interrupter contacts 404 so as to prevent their subsequent operation from interfering with the switch control circuit. Responsive to the operation of armature 415, stepping magnet 403 operates in the manner of a buzzer and moves the wipers 401 and 402 step by step until they again reach their normal position at which time wiper 401 is in engagement with an ungrounded bank contact, resulting in the opening of the circuit of start relay 411. Start relay 411, however, being slow acting does not deenergize immediately.

In the selector D, Fig. 2, each time line relay 115 deenergizes in response to the series of three interruptions produced in its circuit in the director as hereinbefore described, it closes a circuit for vertical magnet 122 as follows: from ground by way of the resting contact of armature 134 and said armature, armature 126 and its resting contact, armature 128 and its working contacts, series relay 117, conductor 102, armature 70 and its resting contact, conductor 101, and vertical magnet 122 to battery. Since line relay 115 is deenergized three times, this circuit is closed three times and vertical magnet 122 operates to raise the wipers 136-138, inclusive, step by step until they stand opposite the third level of bank contacts. Relay 117 is energized in series with vertical magnet 122 upon the first impulse of current being delivered to the latter and, being slow acting, maintains its armature attracted throughout the vertical movement. By the joint action of relay 117 and off normal springs 135, which close upon the first vertical step, a circuit is completed from the grounded release trunk conductor 72, through armature 129 and its working contact, off normal springs 135, and interrupter contacts 124 for stepping relay 118. Upon energizing, stepping relay 118 closes a locking circuit for itself at armature 130, and at armature 131 prepares a circuit for rotary magnet 123.

At the end of the vertical movement, series relay 117 deenergizes and completes at armature 129 a circuit for rotary magnet 123. Rotary magnet 123 therupon energizes and advances wipers 136-138, inclusive, into engagement with the first contact in the level opposite which they are now standing and, near the end of its stroke, opens the circuit of stepping relay 118. Stepping relay 118 accordingly deenergizes and opens the circuit of rotary magnet 123 at armature 131, whereupon rotary magnet 123 deenergizes also and again closes its interrupter contacts 124.

The further operation depends upon whether the trunk terminating in the first set of bank contacts is busy or idle. Assuming that it is idle, switching relay 119 energizes right away and switches the connection through to the trunk. In case it is busy,

however, switching relay 119 is short circuited by the ground potential encountered on the busy test contact by test wiper 137 and does not energize. Stepping relay 118, 5 however, is energized by this same ground potential and again closes the circuit of the rotary magnet 123, whereupon the switch wipers are advanced into engagement with the next set of bank contacts. This alternate 10 operation of stepping relay 118 and rotary magnet 123 continues, as described, until an idle trunk is reached, which trunk it will be assumed is the one terminating in bank contacts 139-141, inclusive. When such idle 15 trunk is reached, switching relay 119, being no longer short circuited, energizes in series with stepping relay 118. Stepping relay 118, however, does not energize at this time on account of the high resistance of switching relay 119. Upon energizing, switching relay 119 removes ground from armature 126 of line relay 115, at armature 134, thereby opening the circuit of the slow acting release relay 116; disconnects test wiper 137 from the 20 junction of its own winding and that of stepping relay 118 and connects it to the ground-ed release trunk conductor 72 at armature 153, thereby making the seized trunk busy immediately and preparing the holding circuit; and at armatures 132 and 135 disconnects talking conductors 71 and 73 from the windings of line relay 115 and extends them by way of wipers 136 and 138, bank contacts 139 and 141, and the associated talking conductors to the associated selector E (which is denoted by the dotted rectangle bearing that reference character). The line and release relays (not shown) of the seized selector now energize in the usual manner and the 25 latter prepares the switch for operation and places the usual ground potential upon the associated release trunk conductor.

Returning now the director, the slow acting start relay 411 of the sender, Fig. 5, de- 30 energizes after an interval and at armature 420 opens the circuit of the slow acting stop relay 410 and at armature 421 places a shunt around armature 418 and its working contact. After an interval slow acting stop relay 410 also deenergizes and again closes the circuit of start relay 411 at armature 419. The interval required for the relays 411 and 410 to fall back one after the other, as de- 35 scribed, is utilized by the selector D, as described above, in effecting the change-over and trunk hunting operations.

When the circuit of the start relay 411 is again closed at armature 419 by relay 410, it energizes again with the above pointed out 40 results including the opening of the circuit of magnet 412 of the vibrator V. The vibrator V again operates to intermittently close the contacts 414 thereby driving the sending switch SEN around step by step through the medium of the stepping magnet 403 which

magnet also interrupts the out going control circuit at armature 405 each time it energizes. Since the second digit also is the digit "3", when, upon the termination of the third interruption in the out going control circuit 45 at contacts 405, stepping magnet 403 deenergizes and advances wipers 401 and 402 into engagement with the fourth set of bank contacts a circuit is completed for stop relay 410 as follows: from ground by way of stop conductor control wiper 654, the second office 50 digit stop conductor 522, wiper 512 of the office register OR, the bank contact upon which it is standing, conductor 542, the associated IDF jumper, the third impulse stop conductor 583, the fourth contact in the bank of wiper 402 of the sending switch SEN, wiper 402, and stop relay 410 to battery. The resulting energization of stop relay 410 55 terminates the second office code digit 3 in the hereinbefore described manner and accordingly opens the circuit of stepping magnet 651 of the sequence switch S' whereupon the wipers of the said sequence switch are advanced into engagement with the third set of bank contacts.

The advance of the wipers of the sequence switch S' onto the third set of bank contacts results in ground being placed upon the third office digit stop conductor 523 by the stop conductor control wiper 654. A circuit is 60 thereupon closed over stop conductor 523, wiper 513, the bank contact upon which it is standing, conductor 543, the associated IDF jumper, skip conductor 510, interrupter contacts 652 and stepping magnet 651 to battery. Stepping magnet 651 is accordingly operated 65 to interrupt its own circuit at contacts 652, resulting in the wipers of the sequence switch being advanced into engagement with the fourth set of bank contacts. This results in ground being placed on the fourth office digit stop conductor 524 by the stop conductor control wiper 654, closing a circuit over conductor 524, wiper 514, the bank contact on which it is standing, conductor 544, the associated IDF jumper, and thence as above traced for the stepping magnet 651 of the sequence switch S'. The stepping magnet 651 is again 70 operated and interrupts its own circuit at contacts 652, resulting in the wipers of the sequence switch being advanced into engagement with the next set of bank contacts.

The above described operations of the sequence switch S' have occurred in a very 75 small fraction of a second and are completed long before the sender is in position to transmit the next digit which is the first digit 0 in the subscriber's number, the office code 80 33 having been transmitted as described above.

It will be noted that only one skip conductor has been provided and that this skip conductor is used for skipping a plurality of code digits, as pointed out above. This skip conductor may be used in skipping the sec- 85 130

ond, or even the first code digit, as well as the third and fourth, as pointed out. In fact, in case it is so desired, all four of the code jumpers may lead to the skip conductor in 5 which case the skipping process begins immediately upon the grounding of start conductor 357 and the first digit sent out is the first subscriber digit registered. This situation may arise in some cases where a plurality 10 of levels of the first selectors, say nine, are used to obtain access to the local hundreds selectors, and access to the other offices of the system is gained through the remaining level or levels of the first selectors.

15 In response to the transmission of the second office digit 3, the selector which was seized by the selector D in response to the first office digit 3, raises its wiper to the third level and seizes a trunk extending to the desired office and terminating in an incoming thousands selector.

As pointed out hereinbefore, the sending out of the office code was initiated responsive to the placing of ground on start conductor 20 357, by wiper 354 of the sequence switch S and, it will be remembered, occurred after the second office digit had been registered. The start conductor 357, it will be noted, is connected with only the first four contacts in 25 the bank of the start conductor control wiper 655 of the sequence switch S', and accordingly the ground on start conductor 357, is not effective in again starting the sender after the sequence switch S' has moved beyond the 30 fourth contact, as it has already done. The starting of the sending mechanism for the remaining digits in the number is controlled by the digit registers DR-1-DR-4, inclusive, by means of which the four subscriber digits of a number are registered. It is obvious that a digit can not be sent out before it is received, and accordingly the sending mechanism must not be again started until the first digit register DR-1 has been operated. In known director systems, a pair of off normal contacts are provided for each digit register, which in connection with a slow acting relay in series with the operating magnet of the digit register, control the 40 starting circuit for the sending out of that digit. The slow acting relay is provided to hold the circuit open after the associated off normal contacts are closed and until the complete digit is registered, in order to insure that the sending mechanism does not start so quickly that it may overtake the register before it has completed its operation.

The present invention provides a new and improved method for controlling the starting circuit, whereby the above mentioned relays are done away with and the register off normal contacts alone control the starting ground. The first register switch does not exercise any control over the starting circuit 60 and the sender is started to send out the first

subscriber digit responsive to the second digit register moving from its normal position and closing its off normal contacts. Then, since it must send out the first digit before it can start sending out the second one, there is no 70 danger of the sender overtaking the second digit register, and the starting ground supplied by the second digit register may be used to start the sender to send out the second subscriber digit also. This, in fact, has been 75 done, and the off normal contacts 371 of the second digit register DR-2 apply the ground to conductor 361, which is multiplied to the fifth and sixth contacts in the bank of the start conductor control wiper 655 of the sequence switch S'.

Similarly, the off normal contacts 372 of the fourth digit register DR-4 apply starting ground to conductor 362 as soon as the wiper 346 of the fourth digit register DR-4 85 moves off normal and this ground is extended to the seventh and eighth contacts in the bank of wiper 655 of the sequence switch S'.

It is apparent from the above explanation that in case a calling subscriber does not dial 90 the first subscriber digit immediately after completing the dialling of the two office digits, the retransmission is held up upon the termination of the office code and the sender is not again started until conductor 361 is 95 grounded responsive to the calling of the second subscriber digit. It is also apparent that the same occurs in case the subscriber waits between the calling of the first subscriber digit and the second subscriber digit. 100 The same rule applies to the retransmission of the third and fourth subscriber digits.

In the following description it will be assumed that the subscriber does not hesitate, but having once started, completes the dialling of his number without waiting more than the usual time between successive digits, in which case it is quite obvious that the director does not "catch up" on account of the fact that it must wait until the first two digits 110 are registered before it can start to retransmit.

The stop conductor control wiper 654 is now in engagement with the bank contact in which the first subscriber digit stop conductor 115 363 terminates. Ground is accordingly extended over conductor 363 to wiper 345 of the first digit register DR-1, which wiper is in engagement with the tenth bank contact. This contact is left dead owing to the fact 120 that it is not necessary to multiple the tenth impulse stop conductor to the digit registers or to the intermediate distributing frame on account of the fact that the corresponding contact in the bank of wiper 402 of the sending switch SEN is permanently grounded, there being no necessity for sending more than ten impulses in any one series. Accordingly, when the sender starts to operate to send out the first subscriber digit 0, it con- 125 130

tinues its operation until wiper 402 has taken ten steps, at which time it encounters the above mentioned permanently grounded contact in its bank and stop relay 410 is energized with the hereinbefore described results. The sequence switch S' is accordingly operated to advance its wipers into engagement with the next set of bank contacts, whereupon the stop conductor control wiper 654 grounds the second subscriber digit stop conductor 364.

The second digit register DR-2 having been set upon the ninth bank contact, the second subscriber digit 9 is terminated when stop relay 410 energizes over the following circuit: from ground by way of the stop conductor control wiper 654 of the sequence switch S', the second subscriber digit stop conductor 364, wiper 344 of the second digit register DR-2, the ninth associated bank contact, the ninth impulse stop conductor, the corresponding contact in the bank of wiper 402 of the sending switch SEN, wiper 402, and stop relay 410 to battery.

At the termination of the transmission of the second subscriber digit 9, the wipers of the sequence switch S' are moved into engagement with the seventh set of bank contacts, and after the eight impulses of the third subscriber digit 8 have been transmitted, stop relay 410 is energized over the following circuit: from ground by way of stop conductor control wiper 654, the seventh associated bank contact, the third subscriber digit stop conductor 365, wiper 345 of the third digit register DR-3, the eighth associated bank contact, the eighth impulse stop conductor, the corresponding contact in the bank of wiper 402 of the sending switch SEN, wiper 402, and stop relay 410 to battery.

After the usual interval following the termination of the third digit 8, the fourth digit 7, is transmitted in the usual manner and is terminated upon the energization of stop relay 410 over the following circuit: from ground by way of stop conductor control wiper 654 of the sequence switch S', the fourth subscriber digit stop conductor 366, wiper 346 of the fourth digit register DR-4, the seventh associated bank contact, the seventh impulse stop conductor, the corresponding contact in bank of the wiper 402 of the sending switch SEN, and thence to battery by way of wiper 402 and stop relay 410. Upon the energization of stop relay 410, the interruptions being produced in outgoing control circuits are terminated in the usual manner and the circuit of stepping magnet 651 of the sequence switch S' is opened, whereupon the wipers of the said sequence switch S' are advanced into engagement with the ninth set of bank contacts and wiper 656 closes a circuit for switching relay 409, Fig. 4, as follows: from ground by way of ninth contact in the bank of wiper 656 of

the sequence switch S', wiper 656, switching conductor 354, normally closed contacts controlled by armature 319 of switching relay 309, Fig. 4, and relay 309 to battery. Relay 309, upon energizing, opens its initial circuit and closes a locking circuit for itself at armature 319, and at armature 318 disconnects conductor 303 from the operating circuit and connects it to the conductor 360, which is grounded through resistance 638, Fig. 7. This latter operation results in the energization of switching relay 48 of the repeater R over the previously traced circuit. Switching relay 48, upon energizing, unites the two sections of the trunk at armatures 68 and 71, and at armature 69 opens the circuit of switching relay 81 of the secondary switch SS and completes a locking circuit for itself through armature 66 and its resting contact, and at the same time, closes the previously traced circuit through armature 87 and its working contact of switching relay 81 for stepping magnet 62 of the secondary switch SS. Accordingly, when switching relay 81 eventually lets go and frees the director, stepping magnet 82 deenergizes and advances the associated wipers into engagement with the next set of bank contacts.

In the director, release relay 308 deenergizes responsive to the removal of the ground potential from release trunk conductor 302 when it is freed in the above described manner, and disconnects the common lead 321 at armature 315, at the same time closing the three restoring circuits of the director at armatures 314, 316, and 317. Armature 314 and its resting contact, it will be noted, are connected through conductors 355 and 356 in multiple with armature 415 and its working contact, of stop relay 410 of the sender SEN. This circuit is provided to restore the sender SEN to normal in case the director is freed while the sender is not in normal position.

Responsive to the placing of ground upon conductor 352 by armature 316, of release relay 308, Fig. 4, a circuit is closed through the bank of wiper 653 of the sequence switch S' and said wiper, and interrupter contacts 652 for stepping relay 651 of the sequence switch S'. Stepping magnet 651 thereupon interrupts its own circuit and advances the associated wipers to their normal position.

Responsive to the placing of ground on release conductor 353 by armature 317 of release relay 308, a circuit is closed for release magnet 502 of the office register OR through off normal contacts 501; a circuit is closed for release magnet 332 of the sequence switch S through off normal contacts 336; a circuit is closed through off normal contacts 341 for release magnet 340 of the digit register DR-1; and similar circuits are closed for the release magnets of the remaining digit registers DR-2-DR-4, inclusive. Accordingly the wipers of all these switches are

restored to normal position in the usual manner. The director is now completely restored to normal and is ready to be used in a subsequent call.

- 5   Returning now to the established connection, it may be pointed out that the desired subscriber is, of course, signalled automatically, and when he responds the conversation may be carried on in the usual manner. Immediately upon the response of the called subscriber the current flow is reversed in the established connection in the usual and well known manner, and as a result, the two windings of the electro polarized relay 45, of the repeater R, assist each other in energizing the relay. Upon energizing, relay 45 closes a circuit at armature 59 for relay 41. Relay 41, upon energizing, inserts the left hand winding of impedance coil 50 in the bridge 10 across the talking conductors at armature 53, so as to improve the talking circuit, and at armatures 51 and 52 reverses the direction of the current flow in the calling line. This latter operation does not have any particular utility in the present case, but may be used whenever and wherever desired for giving supervision to calling PBX operators, or for operating calling subscribers' meters and the like.
- 20   When the calling subscriber replaces his receiver at the end of the conversation, the circuit of line relay 44 of the repeater R is opened. Line relay 44 thereupon deenergizes and opens the bridge across conductors 71 and 73 at armature 35, and at armature 57 opens the initial circuit of release relay 46 and places a short circuit around the said relay. After an interval the slow acting release relay 46 deenergizes and opens the circuit of switching relay 48 at armature 61, whereupon switching relay 48 deenergizes with the results that are apparent. As a further result of the deenergization of release relay 46, it removes ground from release trunk conductor 72 at armature 60, resulting in the deenergization of switching relay 14 of the line switch C and switching relay 119 of the selector D. The deenergization of switching relay 119 of the selector D results in the closure of the circuit of release magnet 120 at armature 134. This circuit includes armature 126 and its resting contact, armature 128 and its resting contact, and off normal contacts 121. Release magnet 120, upon energizing, restores the selector D to normal in the usual manner. The entire connection is now released and the apparatus involved is ready to be used in another call.
- 30   In order to explain the arrangement provided for adjusting the resistance of the outgoing loop in the director in accordance with the length of the inter-office trunks encountered in setting up a connection, it will be assumed that the subscriber at substation A desires to call a subscriber whose line terminates 35 in office 80. It will be assumed further that one of the trunks that must be taken into use when this office is called is exceptionally long, and accordingly a change in the resistance of the controlling loop outgoing from the director is desirable.
- 40   Referring to Fig. 6, it will be noted that the tenth set of contacts in the eighth level of the office register, denoted as (80) in the drawing, are connected up to send out the office code 3459. The first three jumpers associated with this set of contacts on the IDF connect up to the third, fourth, and fifth ones of regular impulse stop conductors, while the fourth jumper is connected with the ninth impulse stop conductor in the special set which is used only when the associated digit is such that the selector which it operates seizes an extra long trunk.
- 45   In this case, as before, it will be assumed that when the subscriber at substation A removes his receiver, a connection is extended through the line switch C to the repeater R, and thence by way of the secondary switch SS to the director shown in Figs. 4-7, inclusive. Then, when the subscriber manipulates his calling device in accordance with the office digits 8 and 0, the wipers 511-514, inclusive, of the office register OR are brought into engagement with the tenth set of bank contacts in the eighth level in the usual manner and ground is placed upon start conductor 357 by wiper 334 of the sequence switch S, resulting in the sender SEN, Fig. 5, being started in the usual manner to send out the office code. The digit registers DR-1-DR-4, inclusive, are operated as hereinbefore described, and set up the number of the desired subscriber, whatever that number might be.
- 50   The first three digits 3, 4, and 5 of the office code are sent out in the usual manner, but when the wipers 653-656, inclusive, of the sequence switch S' are advanced into engagement with the fourth set of bank contacts at the end of the transmission of the third code digit 5, the stop conductor control wiper 654 applies ground to the fourth office digit stop conductor 524 in the usual manner, thereby completing a circuit through wiper 514 of the office register OR, the bank contact on which it is standing, conductor 534, the associated jumper, the ninth impulse stop conductor in the special set of stop conductors, the normally closed contacts controlled by the left hand armature of the two-step relay 619, and the left hand winding of relay 619 to battery. The left hand winding of relay 619 comprises a relatively small number of turns of wire having a comparatively high resistance, and for that reason, is not able to operate the relay fully. The contacts on the relay marked 1 are operated at this time, while the contacts marked 2 are not operated, this differentiation being taken care 60 of by the normally closed contacts 125 controlled by the right hand armature of the two-step relay 619.
- 60   The contacts on the relay marked 1 are operated at this time, while the contacts marked 2 are not operated, this differentiation being taken care 65 of by the normally closed contacts 125 controlled by the right hand armature of the two-step relay 619.
- 65   The contacts on the relay marked 1 are operated at this time, while the contacts marked 2 are not operated, this differentiation being taken care 70 of by the normally closed contacts 125 controlled by the right hand armature of the two-step relay 619.
- 70   The contacts on the relay marked 1 are operated at this time, while the contacts marked 2 are not operated, this differentiation being taken care 75 of by the normally closed contacts 125 controlled by the right hand armature of the two-step relay 619.
- 75   The contacts on the relay marked 1 are operated at this time, while the contacts marked 2 are not operated, this differentiation being taken care 80 of by the normally closed contacts 125 controlled by the right hand armature of the two-step relay 619.
- 80   The contacts on the relay marked 1 are operated at this time, while the contacts marked 2 are not operated, this differentiation being taken care 85 of by the normally closed contacts 125 controlled by the right hand armature of the two-step relay 619.
- 85   The contacts on the relay marked 1 are operated at this time, while the contacts marked 2 are not operated, this differentiation being taken care 90 of by the normally closed contacts 125 controlled by the right hand armature of the two-step relay 619.
- 90   The contacts on the relay marked 1 are operated at this time, while the contacts marked 2 are not operated, this differentiation being taken care 95 of by the normally closed contacts 125 controlled by the right hand armature of the two-step relay 619.
- 95   The contacts on the relay marked 1 are operated at this time, while the contacts marked 2 are not operated, this differentiation being taken care 100 of by the normally closed contacts 125 controlled by the right hand armature of the two-step relay 619.
- 100   The contacts on the relay marked 1 are operated at this time, while the contacts marked 2 are not operated, this differentiation being taken care 105 of by the normally closed contacts 125 controlled by the right hand armature of the two-step relay 619.
- 105   The contacts on the relay marked 1 are operated at this time, while the contacts marked 2 are not operated, this differentiation being taken care 110 of by the normally closed contacts 125 controlled by the right hand armature of the two-step relay 619.
- 110   The contacts on the relay marked 1 are operated at this time, while the contacts marked 2 are not operated, this differentiation being taken care 115 of by the normally closed contacts 125 controlled by the right hand armature of the two-step relay 619.
- 115   The contacts on the relay marked 1 are operated at this time, while the contacts marked 2 are not operated, this differentiation being taken care 120 of by the normally closed contacts 125 controlled by the right hand armature of the two-step relay 619.
- 120   The contacts on the relay marked 1 are operated at this time, while the contacts marked 2 are not operated, this differentiation being taken care 125 of by the normally closed contacts 125 controlled by the right hand armature of the two-step relay 619.
- 125   The contacts on the relay marked 1 are operated at this time, while the contacts marked 2 are not operated, this differentiation being taken care 130 of by the normally closed contacts 125 controlled by the right hand armature of the two-step relay 619.

of by the spring adjustment in the usual manner. At its inner right hand armature, relay 619 locks itself to the grounded conductor 302. This locking circuit is not effective at this time, however, owing to the fact that the right hand winding is short circuited by the ground potential placed on the junction of the two windings through the above traced circuit. The left hand armature of relay 619, 10 on coming into engagement with its associated contact, connects the ninth regular impulse stop conductor to the ninth special impulse stop conductor so as to terminate the last office digit 9 in the usual manner. Accordingly, when the sender, which is subsequently started, has sent out nine impulses in this digit, wiper 402 comes into engagement with the bank contact in which the ninth impulse stop conductor terminates, thereby 20 completing a circuit as previously traced to the left hand armature of relay 619 and thence by way of the ninth impulse stop conductor, the corresponding contact in the bank of wiper 402 of the sender, wiper 402, and stop relay 410 to battery. The resulting energization of relay 410 causes this digit to be terminated in the usual manner and also causes the circuit of stepping magnet 651 of the sequence switch S' to be opened, whereupon 30 on the associated wipers are advanced another step, thereby opening the previously traced circuit for the left hand winding of relay 619. When this occurs the locking circuit through the right hand winding of said relay becomes 35 effective, whereupon the relay pulls up all the way, thereby disconnecting the junction of its two windings from the associated impulse stop conductor at the normally closed contacts controlled by its left hand armature, and placing a shunt around resistance 637 in the outgoing loop at its right hand armature, so as to compensate for the extra length of the trunk line assumed to be taken into use by the selector operated in response to the office digit which is sent out. 40

The subscriber digits of the number are retransmitted in the usual manner, the total loop resistance being about the same as the average, regardless of the extra long trunk taken into use, on account of the above mentioned elimination of resistance 637, Fig. 7.

In order to explain the feature of the invention having to do with the notification of the toll recording operator of the class to which the calling subscriber's line belongs, it will now be explained how a connection is extended to the toll recording operator. As has been briefly mentioned before, the calls to the toll recording operator are automatically sorted by the director and then sent in over three different groups of trunks depending upon the class to which the calling line belongs. This necessitates the sending out by the director of three different codes, all responsive to the calling of the toll recording

operator. It has been assumed that these three codes are 292, 293, and 290, 292 being the code used for unlimited service, 293 being the code used for limited service, and 290 being the code used for the class of lines not entitled to any long distance service. It has been assumed that the toll recording operator is listed in the directory as 60. Accordingly, the corresponding set of contacts in the bank of the office register OR, Fig. 6, are jumpered 70 on the IDF in accordance with the above mentioned codes. The first two contacts are jumpered to the second and ninth impulse stop conductors in the usual manner, while the third contact of the set is jumpered 75 to conductor 506 which extends to the armature 636 of the two step relay 602. This relay is controlled according to the class of the calling line and it may remain normal; pull half way up; or pull all the way up. When the 80 relay remains normal, as it does when an unlimited service line is calling, conductor 506 remains connected through armature 636 to conductor 507, and when relay 602 pulls all the way up, as it does when a limited service line is calling, conductor 506 is disconnected 85 from conductor 507 and is connected to conductor 508 instead, and when relay 602 pulls part way up, conductor 506 is disconnected 90 from conductor 507 but is not connected to conductor 508, thereby automatically causing the digit 0 to be transmitted 95 when the sequence switch S' arrives in the proper position.

Assuming now that the subscriber at substation A, whose line it is assumed is an unlimited service line, desires to call the toll recording operator, and assuming further that the line switch C seizes the repeater R, and that the secondary switch SS seizes the 100 director shown in the drawings, the calling subscriber dials the number 60 of the toll recording operator, resulting in the wipers 511-514, inclusive, of the office register OR being set upon the corresponding bank contacts. Since the calling line is an unlimited service line, and since armature 18 of the associated line switch C is consequently not connected up, the discriminating relay 602, Fig. 7, of the director is accordingly not energized. Then, after the director has sent out the first two code digits 2 and 9 in the usual manner, the wipers of the sequence switch S' are advanced into engagement with the third set of bank contacts and ground is 105 placed on the third wiper of the office register OR. Then, when the sender is again started and two interruptions in the outgoing control circuit have been produced, a circuit is closed for stop relay 410, Fig. 5, 110 as follows: from ground by way of the stop conductor control wiper 654 of the sequence switch S', the third associated bank contact, the third code digit stop conductor 523, wiper 513 of the office register OR, the bank 115

contact on which it is standing, the associated IDF jumper, conductor 506, armature 636 of relay 602 and its resting contact, conductor 507, the associated jumper, the second impulse stop conductor, the corresponding contact in the sender bank, wiper 402 of the sender SEN, and stop relay 410 to battery. The energization of stop relay 410 results in the third code digit 2 being terminated in the usual manner, and also results in the usual advance of the wipers of the sequence switch S'. Upon being advanced, stop conductor control wiper 654 of the sequence switch S' places ground on the fourth wiper 514 of the office register OR, thereby extending a ground potential through the bank contact on which the said wiper is standing and the associated jumper to the switching conductor 603, and thence by way of the fourth contact 70 in the bank of wiper 656 of the sequence switch S', switching conductor 354, normally closed contacts controlled by armature 319, and relay 309 to battery. Upon the energization of switching relay 309, the connection 75 is switched through and the director is freed and reverts to common use in the usual manner.

If it is assumed for the moment that the line of substation A is a limited service line, 80 then the upper terminal of the resistance 9, associated with the line switch C, is connected to armature 18. Then, assuming that the subscriber at substation A is calling; that line switch C has selected the repeater R; and 85 that the secondary switch SS has selected the director shown, a circuit is completed for relay 602, Fig. 7, as follows: from ground by way of the upper terminal of resistance 9, Fig. 1, the associated jumper, armature 18 and its working contact, wiper 25, bank contact 29, conductor 33, working contact of armature 84 and said armature, wiper 90 of the secondary switch SS, bank contact 95, conductor 301, and relay 602, Fig. 7, to battery. Relay 602 accordingly pulls all the 90 way up and disconnects conductor 506 from conductor 507 and connects it to conductor 508, which is connected by means of a jumper to the third impulse stop conductor. Accordingly the limited service code 293, instead of the unlimited service code 292 is sent out.

If the line of the substation A belongs 95 to the class not entitled to any long distance service at all, armature 18 of the line switch C would be connected to the lower terminal of the resistance 9, and, in that case, if the line were calling and if the directors shown were used, relay 602 would pull up only half way and neither conductor 507 nor 508 would be connected to conductor 506, and the digit 0 would be sent out when the sequence switch S' arrives in the third position.

The above described arrangement for sorting 100 the calls to the toll recording operator, is

used also for sorting calls to the express operator. By express operator it is meant the operator who handles calls to nearby toll centers as pointed out hereinbefore. The same relay 602 varies the express code in about the 70 same way as it varies the long distance code. It is assumed that the express operator is listed in the directory as 50 and that the first two code digits are 8 and 1, respectively, while the last digit may be 7, 8, or 9, depending 75 upon the class to which the calling line belongs. This may be seen by looking at Figs. 6 and 7 of the drawings, and it is thought that in view of the explanation above given for calls to the toll recording operator, it is 80 not necessary to explain in detail how the calls are sorted out for the express operator, a glance at the drawings being all that is necessary to understand this.

As mentioned before, arrangements have 85 been made for providing extra battery feed when a call is trunked to the express operator so as to improve the transmission at such times, thereby avoiding the use of a special set of trunks.

In order to explain how this is done, it will be assumed that the subscriber at substation A desires to converse with the subscriber at substation B, Fig. 3. It will be assumed further that when the subscriber at substation A removes his receiver, the line switch C seizes the repeater R and the secondary switch SS seizes the director shown in the drawing. That being the case, when the subscriber dials the number 50 assigned to the express operator, the wipers of the office register OR are brought into engagement with the tenth set of bank contacts in the fifth level. The first two code digits 9 and 2 are sent out in the usual manner, resulting in the selector D, Fig. 2, being raised to the ninth level to select a second selector such as E, and resulting in the wipers of the selector E being raised to the second level, whereupon a third selector, such as the selector F, is 100 seized.

Since the line of substation A is an unlimited service line, armature 18 of the line switch C is not connected up, and relay 602, Fig. 7, is not energized. Accordingly, when the wipers of the sequence switch S' arrive upon the third set of bank contacts at the termination of the second code digit 2, ground is extended over the third contact in the bank of wiper 654, conductor 523, wiper 513, the 105 bank contact on which it is standing, the associated IDF jumper, conductor 516, normally closed contacts controlled by armature 633, and relay 601 to battery. Relay 633 thereupon energizes and places a shunt around resistance 638 at armature 631 so as to prepare a circuit for placing in the above mentioned extra battery feed. As a further result of the energization of relay 601, it closes a locking circuit for itself and opens its 110 115 120 125 130

initial circuit at armature 633, and at armature 632 extends conductor 516 through armature 634 and its resting contact, conductor 517, and the associated IDF jumper, to the 5 seventh impulse stop conductor 589. Accordingly, when seven interruptions in the outgoing control circuit have been produced, the third code digit 7 is terminated upon the energization of stop relay 410 over the 10 seventh impulse stop conductor 587.

Upon the termination of the third code digit 7, the wipers of the sequence switch S' are again advanced in the usual manner and ground is placed on wiper 514 of the office 15 register OR, by the stop conductor control wiper 654 of the sequence switch S', and is extended from thence by way of the bank contact on which the wiper 514 is standing, and the associated IDF jumper to switching conductor 20 603, and thence by way of the previously traced circuit to battery through switching relay 309, Fig. 4. Switching relay 309, upon energizing, among other things, closes the previously traced circuit for switching relays 47 25 and 48 of the repeater R in series. At this time, however, resistance 638 is short circuited at armature 631 of relay 601, Fig. 7, as hereinbefore described, and the marginally 30 adjusted relay 47 energizes as well as relay 48. Upon energizing, relay 47 closes at armature 65 a circuit for relay 42. Relay 42, upon energizing, at armatures 54 and 55 disconnects 35 armatures 51 and 52 of the reversing relay 41 from the windings of line relay 44 and connects them instead to the windings of the low wound battery feed relay 43. As a further result of the energization of the marginally 40 adjusted relay 47, it shifts the locking circuit of relay 48 at armature 66 so that it includes its own winding and the upper winding of relay 48 instead of the lower winding of relay 48. The energization of relay 48, which occurs at this time, results in the locking circuit 45 of relays 47 and 48 being closed in series, in addition to the other circuit changes hereinbefore described.

In response to the sending out of the third code digit 7 by the director as hereinbefore described, the selector F is raised opposite 50 the seventh level of bank contacts and selects an idle trunk extending to the express operator's position. For example, the trunk comprising conductors 151 and 152 which, as hereinbefore mentioned, are in the group over 55 which the unlimited service calls are received. Responsive to the seizure of the trunk terminating in the cord circuit CC, Fig. 3, line relay 206 is energized over conductors 151 and 152 and through the left hand windings 201 60 and 202 of the repeating coil and closes a circuit for the supervisory lamp L at armature 213.

When the operator notes the lighted condition 65 of the lamp L, she operates her listing key K, thereby connecting the conductors of

her head set with the talking conductors of the cord circuit so as to get into communication with the calling subscriber. Spring 219 of the key K closes a circuit at this time for relay 207 which energizes and locks itself at armature 70 216 to ground through armature 214 and its working contact of the line relay, and at armature 215 opens the circuit of the supervisory lamp L. When the operator learns 75 from the calling subscriber the desired number, she restores the listing key K and pushes the order wire push button P and informs the distant operator of the number. Assuming that the distant operator assigns the trunk comprising conductors 221 and 222, the express operator inserts the plug of the cord circuit CC into the jack J, thereby closing a circuit for sleeve relay 208, which thereupon energizes and prepares a circuit for the supervisory lamp L which will be closed on the subsequent deenergization of line relay 206. As 80 a further result of the plug of the cord circuit CC being inserted into the jack J, a circuit is closed over the trunk conductors and the left hand repeating coil windings of the cord circuit CC' for the high resistance supervisory relay 236. Relay 236 accordingly energizes, but relay 205 of the cord circuit CC does not energize at this time on account of the high resistance of relay 236. The energization 85 of relay 236 results in the supervisory lamp L' becoming lighted.

The operator at the called manual exchange, upon the receipt of the desired number, tests the called line by tapping the tip 100 of the plug of the cord circuit CC' against the sleeve contact of the jacket J'. Assuming that the called line is idle, the operator inserts the plug into the jack, whereupon sleeve relay 238 energizes in series with the cut-off relay of the line and extinguishes the supervisory lamp L'. Sleeve relay 238 also connects up the tip and ring conductors of the plug at armatures 245 and 247, whereupon ringing current is intermittently projected out over 105 the called line through the working contact of armature 241 of relay 236 and said armature, resting contact of armature 244 and said armature, and the working contact of armature 247 and said armature, and returns 110 through armature 245 and its working contact, and armature 242 and its resting contact, to battery through the upper winding of ring cut-off relay 237. The small condenser 115 248, which is bridged around armature 242 and its working contact, permits a sufficient quantity of ringing current to pass there-through to give an audible ringing signal to the calling subscriber in the usual manner.

When the subscriber at substation B responds to the ringing of his bell by removing his receiver, a direct current bridge is closed across the conductors of his line whereupon ring cut-off relay 237 energizes and removes the shunt from around its lower winding at 120 125 130

5 armature 243, thereby becoming locked up in series with sleeve relay 238. As a further result of the energization of ring cut-off relay 237 it disconnects the tip and ring conductors of the plug from its own upper winding and from the ringing lead and connects them through to the right hand repeating coil windings, thereby finally completing the talking circuit. Back bridge relay 235 immediately energizes over the called line and places a shunt around the lower winding of relay 236, whereupon the back bridge relay 205 of the cord circuit CC energizes and reverses the direction of the current flow in the conductors 151 and 152 at armatures 211 and 212. Responsive to this reversal, electro polarized relay 45 in the repeater R, Fig. 1, energizes and completes a circuit for the reversing relay 41. Relay 41 increases the impedance of 10 the back bridge of the repeater by cutting in the left hand winding of the impedance 50 at armature 53, and at armatures 51 and 52 makes the usual transposition of the conductors 31 and 34 which results at this time in the line relay 44 being disconnected and the low resistance battery feed relay 43 being connected up, relay 42 having been energized previously as hereinbefore described. Owing to the fact that the battery feed relay 15 43 is used instead of the somewhat higher resistance line relay 44, a sufficient amount of talking battery is now supplied to the substation A to permit good transmission from the said substation. Responsive to being connected up relay 43 energizes and removes ground from the resting contact of armature 57 at armature 56, so as to prevent the continued short circuiting of release relay 45 at this time which would otherwise occur on account of the fact that line relay 44 is now deenergized.

45 At the termination of the conversation which follows, the two subscribers replace their receivers. When the receiver is replaced at substation B, line relay 235 falls back and removes the shunt from around the lower winding of relay 236, whereupon relay 205 of the cord circuit CC responds by falling back and thereby reverses the current flow in the conductors 151 and 152 back to normal. When this occurs, the electro-polarized relay 45 of the repeater R deenergizes and opens the circuit of relay 41 which deenergizes also and again connects up line 50 relay 44, at the same time disconnecting the battery feed relay 43.

60 When the receiver is replaced at substation A, line relay 44 of the repeater R deenergizes and short circuits release relay 46 at armature 57, and at armature 35 opens the bridge across conductors 71 and 73. Release relay 46, upon deenergizing, causes the automatic switches involved in the connection to be released in the usual manner.

65 Responsive to the opening of the back

bridge of the repeater R, line relay 206 of the cord circuit CC' deenergizes and unlocks the relay 207 at armature 214, and at armature 213 closes a circuit for the supervisory lamp L which has been prepared at armature 217 and its working contact of sleeve relay 208. The express operator, upon noting the lighted condition of the lamp L, pulls out the plug of the cord circuit CC from the jack J. This results in the deenergization of relay 236 of the cord circuit CC'. When this occurs, the supervisory lamp L' becomes lighted and the operator is thus notified to take down the connection, and when she does so, the cut-off relay in the called line and relays 237 and 238 of the cord circuit CC' deenergize and the entire connection is broken down.

70 It may be pointed out at this time that, heretofore, it has been common practice to place repeaters on the outgoing trunks when it is necessary to give express service, in which case a simple trunk circuit is used in place of the repeater R, and the battery feed for any outgoing call is obtained from the repeater 75 on the outgoing trunk in use. When this is done, in order to secure a low resistance battery feed, there must be a separate group of trunks to the express operator, whose repeaters are made special in order to supply 80 the low resistance battery feed when the express operator is called. This arrangement is uneconomical for the reason that, for the most part, the group of trunks leading to the express operator from any given office, and especially from an outlying office, may be 85 relatively small and inefficient. With the present arrangement, however, no special group of trunks need be provided for calls to the express operators which are completed 90 over the same trunks as calls to the other offices and are split up by the selectors at some point near the office in which the express operator is located.

95 What is claimed is:

100 1. In a telephone system, a closed circuit, an impulse sending mechanism, a vibrating interrupter individual thereto, said interrupter comprising a magnet and an associated pendulum, means for energizing said magnet, means for subsequently deenergizing said magnet to permit said pendulum to vibrate independent of further influence from said magnet, and electromagnetic means controlled by said pendulum for causing said mechanism to intermittently interrupt said circuit.

110 2. In a telephone system, a circuit, an impulse sending mechanism, a vibrating interrupter individual thereto, said interrupter comprising a magnet and an associated pendulum, means for energizing said magnet, means for subsequently deenergizing said magnet to permit said pendulum to vibrate independent of further influence from said 115 120 125 130

magnet, means controlled by said pendulum for causing said mechanism to send impulses of current through said circuit, and means for again energizing said magnet to terminate said impulses, by attracting said pendulum, when any desired number of impulses have been sent.

3. In a telephone system, two progressively movable registers for registering digits in a telephone number, means for operating the first register and for subsequently operating the second one, sending mechanism, means for associating said mechanism with said registers in the order in which they are operated, a starting circuit for said sending mechanism, an open point in said starting circuit, and means for closing said open point responsive to the operation of the second of said registers whereby said sending mechanism is started to send out the digit registered by the first of said registers.

4. In a telephone system, lines divided into a plurality of classes, registering mechanism set under the control of a calling line to register a called number, sending mechanism, and means controlled by said sending mechanism for sending out a number in accordance with the setting of said registering mechanism and also in accordance with the class to which the calling line belongs.

5. In a common battery telephone system, a calling line, a register set under the control of said line, and means controlled by said register for regulating the flow of talking battery supplied to said line in accordance with the class of the connection set up.

6. In a telephone system, trunks over which connections may be set up, an organization of equipment for registering telephone numbers and for retransmitting current impulses representing said numbers over said trunks, an outgoing control circuit over which said retransmission is effected, and means controlled by said organization of equipment for varying the electrical characteristics of said control circuit in accordance with the length of one of the trunks involved in a connection.

7. In a telephone system, a plurality of organizations of equipment, each having registering and retransmitting apparatus, a selecting switch for seizing an idle one of said organizations, means for subsequently freeing the seized organization, and means thereupon effective for associating said switch with another of said organizations.

8. In a telephone system, a calling line, a trunk circuit, a call director, means for extending a connection from said line to said trunk circuit, means for thereupon connecting said trunk circuit with said director whereby the desired number may be received and retransmitted, a selector switch, a stepping magnet therefor, said magnet having a circuit, a timing device, means controlled by

said device for disconnecting said director from said trunk circuit and for connecting said trunk circuit with said switch, and means controlled by the last named means for opening said magnet circuit so as to remove 70 said selector from under the control of said line.

9. In a telephone system, a control circuit, a magnet, a pair of contacts controlled by said magnet for sending impulses over said 75 circuit, and means operated mechanically by said magnet for counting the impulses produced in said circuit.

10. In a telephone call director, a register, subscriber controlled means for setting said 80 register, a sender controlled by said register to transmit a plurality of series of impulses, a separate control conductor for each of said series of impulses, a single skip conductor, and means controlled over said skip conductor for skipping or cancelling any or all of said series of impulses, the skipping of any one series of impulses being effected by connecting the corresponding one of said control conductors to said skip conductor. 85

11. In combination, a sending device comprising a tuned reed and a magnet for maintaining said reed in a flexed position when energized, a variably operable register, means for operating said register, means for deenergizing said magnet to permit said reed to vibrate freely, a stepping device controlled electromagnetically by said reed to advance one step upon each cycle of operation of said reed, and a circuit closed by said stepping device 100 for energizing said magnet to again flex said reed upon the completion of a number of steps corresponding to the operated position of said register. 95

12. In combination, a tuned vibratory reed, 105 a magnet for maintaining said reed in a flexed position when energized, a register having a plurality of positions, means for setting said register into one of said positions, means for deenergizing said magnet to release said reed, and a circuit arrangement controlled by said reed for bringing about the energization of said magnet to stop said reed from vibrating when it has gone through a number of cycles of operation corresponding to the particular set position of said register. 110

13. In a telephone system, lines divided into a plurality of classes, registering mechanism set under the control of any calling one of said lines to register a called number, 120 sending mechanism for transmitting a number in accordance with the setting of said registering mechanism, and a class registering device controlled from the calling line independent of selective control by the calling subscriber for altering the number transmitted. 125

14. In a common battery telephone system, a calling line, a register set under the control of said line, and means controlled jointly 130

by said register and by the party called for altering the flow of talking battery supplied to the calling line.

15. In a common battery telephone system, 5 a calling line, a register set under the control of said line, and means selectively controlled by said register for increasing the current flow over the calling line responsive to the response of the party on the called line.
- 10 16. In a telephone system, trunk lines over which connections may be set up, registering and sending mechanism for registering telephone numbers and for retransmitting current impulses representing said numbers, automatic switches responsive to the retransmission of the digits of one of said telephone numbers for progressing a call through one after another of said trunk lines in serial relationship, a circuit over which said retransmission is effected, and means automatically operated between the transmission of two successive digits for varying the condition of said circuit in accordance with the electrical characteristics of the trunk line taken into 20 25 use responsive to the transmission of the last digit transmitted.

17. In a telephone system, an automatic switch having a wiper and circuit controlled means for bringing said wiper successively 30 into engagement with bank contacts, a switching relay, a circuit for energizing said relay responsive to said wiper being brought into engagement with an idle contact, means for subsequently opening the circuit of said 35 switching relay and for thereupon closing a circuit to advance said wiper again, and contacts controlled by said switching relay for again opening said latter circuit.

18. In a director, a series of progressively 40 movable registers, means for setting said registers in turn, sending mechanism for transmitting series of impulses in accordance with the settings of said registers, respectively, and means controlled by one of said registers 45 for starting said sender to transmit impulses in accordance with the setting of the preceding register.

19. In a director, a series of registers, 50 means for setting said registers in turn, sending mechanism for transmitting series of impulses in accordance with the settings of said registers, respectively, means controlled by each of a plurality of said registers for starting said sending mechanism, and means controlled each time by a preceding register for 55 stopping said sending mechanism.

20. In a director, two progressively movable registers, a sending mechanism, means for setting said registers successively, a circuit closed by the last register set for starting said mechanism, and a circuit controlled by the first register set for stopping said mechanism.

21. In an automatic impulse transmitter, 65 a counting switch, a pendulum for operating

said switch, means for sending impulses while said pendulum is in operation, and means controlled by a progressively movable wiper of said switch for stopping said pendulum.

70

22. In an automatic impulse transmitter, a counting device, a pendulum for sending impulses to actuate said counting device, an outgoing control circuit, means for sending an impulse over said circuit each time said pendulum operates said counting device, and means controlled by said counting device for stopping said pendulum.

75

23. In combination, a counting switch, a pendulum, a circuit controlled by said pendulum for operating said switch, and a circuit controlled by said switch at any predetermined point in its operation for stopping said pendulum.

80

24. In combination, a counting switch having progressively movable wipers, a pendulum, a circuit controlled by said pendulum for operating said switch, and circuits controlled by the wipers of said switch for stopping and starting said pendulum.

85

25. In combination, a counting switch, a pendulum, a circuit controlled by said pendulum for operating said switch, means for starting the pendulum while the switch is in normal position, and means controlled by the switch for stopping the pendulum when the switch reaches a variable predetermined position.

90

26. In combination, a counting switch, a pendulum, a circuit controlled by said pendulum for operating said switch, means for starting the pendulum while the switch is in normal position, means controlled by the switch for stopping the pendulum when the switch reaches a predetermined position, 100 means for returning the switch to normal independent of said pendulum, and means for automatically restarting the pendulum.

105

27. In an automatic impulse transmitter, a control circuit, a sending device for producing a variable series of impulses in said circuit, a counting device for counting said impulses, a normally inactive interrupter mechanism for controlling both said devices, and means for rendering said mechanism operative only while impulses are being sent.

110

28. In an automatic impulse transmitter, a control circuit, a sending device for producing impulses in said circuit, a counting device for counting said impulses, an interrupter mechanism controlling both said devices but normally restrained against operating, means for releasing said mechanism to send a variable series of impulses, and means for again restraining said mechanism from operating as soon as said counting device has counted the required number of impulses.

115

29. In a telephone system, a plurality of classes of subscribers' lines, a manual switch-

120

125

130

- board, a plurality of groups of trunks extending to said switchboard, automatic switches for extending calling lines to said switchboard over said trunks, a director accessible to any calling line for registering the number assigned to said switchboard and for sending directive series of impulses for controlling said switches, and class discriminating means in said director for causing the 5 same to modify one series of impulses to selectively operate one of said switches partly according to the class of the calling line so as to route calls from each class of lines over a different group of trunks.
- 10 30. In a telephone system, a plurality of classes of subscribers' lines, a manual switchboard, a plurality of groups of trunks extending to said switchboard, automatic switches for extending calling ones of said 20 lines to said switchboard over said trunks, a director accessible to any calling line for registering the number assigned to said switchboard, means for translating such registration into a code, means in said director 25 for sending series of impulses corresponding to the code for setting a train of said switches, and means operating according to the class of the calling line for altering the code so that calling lines of each class are extended 30 to said switchboard over a different one of said groups of trunks.
31. In a director, a register, two contact sets in said register corresponding to the call 35 numbers of two different operators' switchboards, means including a distributing frame and temporary connections thereon for translating each number into a code, and a single class relay for altering both codes according 40 to the class of any calling line using the director.
32. In a director, a distributing frame comprising sets of register terminals and a series of digit stop conductor terminals, a 45 second series of terminals corresponding in number to said first series, locking relays, conductors extending from the terminals of said second series to said locking relays, and contacts on each relay for connecting its associated one of said conductors to the corresponding stop conductor terminal.
- 50 33. In a director, a distributing frame comprising sets of register terminals and a series of digit stop conductor terminals, a second series of terminals corresponding in number to said first series, locking relays, conductors extending from the terminals of said second series to said locking relays, contacts on each relay for connecting its associated one of said conductors to the corresponding stop conductor terminal.
- 55 34. In a director, a distributing frame comprising sets of register terminals and a 60 control circuit outgoing from said director, and contacts on each of said relays for altering said circuit.
- 65 35. In a director, a register, a sending mechanism including a counting device, means for connecting a given contact in said register with a contact in said counting device over either of two different paths, and a control relay individual to one path only and responsive whenever the connection is used provided the connection includes the path with which the relay is associated. 70
36. In a director, a register, a sending mechanism including a counting device, means for connecting a given contact in said register with a contact in said counting device over either of two different paths, a control relay individual to one path only and responsive whenever the connection is used provided the connection includes the path with which the relay is associated, a switch control circuit outgoing from said director, and means under control of said relay for altering the electrical characteristics of said circuit. 75
37. In a director, a register, a sending mechanism including a counting device, means for connecting a given contact in said register with a contact in said counting device over either of two different paths, a control relay individual to one path only and responsive whenever the connection is used 80 provided the connection includes the path with which the relay is associated, a switch control circuit outgoing from said director, and means under control of said relay for altering the resistance of said circuit. 85
38. In a telephone system, a trunk line accessible to calling lines, automatic switches for extending said trunk line to called lines, a director and means for connecting it to said trunk line responsive to a call, means in said director for setting different trains of said switches according to the destination of the call, two battery feed retard coils in said trunk line differing in resistance, and means controlled by said director in accordance with 90 the switch train in use for determining which one of said coils will be used to supply talking current to the calling line. 95
39. In a telephone system, a trunk line accessible to calling lines, automatic switches for extending said trunk line to called lines, a director and means for connecting it to said trunk line responsive to a call, means in said director for setting different trains of said switches according to the destination of the 100 105 110 115 120 125 130

call, a line relay in said trunk line for controlling said director and for feeding talking current to the calling line, another battery feed coil in said trunk line, and means controlled by said director in case the call is routed via a particular train of switches for substituting said second coil for said line relay.

40. In a telephone system, a trunk repeater, a line relay in bridge of the talking circuit on the incoming side of said repeater, a relay for reversing the trunk connections to said line relay, a retard coil, and a second relay cooperating with said reversing relay to substitute said retard coil for said line relay.

41. In a telephone system, a trunk repeater, a line relay in bridge of the talking circuit on the incoming side of said repeater, a relay for reversing the trunk connections to said line relay, a retard coil, a second relay cooperating with said reversing relay to substitute said retard coil for said line relay, a director associated with said repeater, and a circuit for said second relay controlled by said director.

42. In a telephone system, a trunk line comprising two normally disconnected sections, a selector in which the second section terminates, said selector having a stepping magnet, a director, a branch of said trunk line for connecting the same with said director, said director having means for controlling said switch, a relay for disconnecting said branch and for uniting said sections, and means for opening the circuit of said stepping magnet whenever said relay is energized.

43. In a telephone system, a trunk line comprising two normally disconnected sections, a selector in which the second section terminates, said selector having a stepping magnet, a line relay in said selector controlled over the second section of said trunk line, contacts on said line relay controlling said stepping magnet, a relay for uniting the two sections of said trunk line, and contacts on said last relay for opening the circuit of said stepping magnet.

44. In a telephone system, two progressively movable registers for registering digits in a telephone number, means for operating the first register and for subsequently operating the second one, sending mechanism, means for associating said mechanism with said registers in the order in which they are operated, a starting circuit for said sending mechanism, an open point in said starting circuit, and means for closing said open point respon-

sive to starting of the operation of the second of said registers and before the completion of said operation whereby said sending mechanism is started to send out the digit registered by the first of said registers.

45. In an impulse sender a counting device, a magnet arranged to drive said device, means for operating said magnet to drive said device a given distance, contacts controlled by said magnet for sending impulses when it is driving said device, and means operated by said device before it has traveled said given distance for preventing said contacts from sending impulses during the remainder of the travel of said device.

46. In a telephone system, a trunk line divided into two sections, means for setting up a telephone connection including both sections in series, and means in said trunk line for supplying talking current to one of the connected lines through one section only of the trunk line and for regulating the strength of the current flow.

47. In a telephone system, a trunk line, means for setting up a telephone connection including said trunk line and for supplying talking current to one connected line through said trunk line, and means individual to said trunk line for regulating the strength of the current flow.

48. In a common battery telephone system, means for setting up a telephone connection between two lines, and means for subsequently regulating the strength of the flow of talking current supplied to one of the connected lines.

49. In a register sender, a distributing frame, a set of terminals on one side of said frame adapted to be selected by the registration of a number, digit bus bars and a "skip" bus bar on the other side of said frame, and jumpers connecting one terminal of said set to a digit bus bar and a plurality of terminals of said set to said "skip" bus bar.

50. In a register sender, a set of terminals, registering apparatus for selecting said terminal sets upon the receipt of a portion of a number, digit conductors and a "skip" conductor, a connection between one terminal of said set and one of said digit conductors, and connections between a plurality of terminals of said sets and said "skip" conductor.

In witness whereof, I hereunto subscribe my name this 13th day of September, A. D. 1923.

MARTIN L. NELSON.
